UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,593, dated August 28, 1894.

Application filed July 31, 1894. Serial No. 519,099. Term of patent 3½ years.

To all whom it may concern:

Be it known that I, CHARLES BOOZE, a citizen of the United States, residing at Buffalo, in the county of Erie and State of New York, 2c
5 have invented and produced a new and original Design for Wall-Paper, of which the following is a specification.

The design consists of a series of festoons of flowers and leaves, and ribbons, arranged 25
10 regularly over the surface of the paper as represented in the accompanying drawing. The border or upper portion of the design is formed of festoons of flowers and leaves and ribbons, said festoons being connected by 25
15 bows of ribbons, and ornamental figures which alternate with the ribbon bows as shown in

the drawing. A narrow band containing a wavy ribbon arranged lengthwise and centrally in the band forms the bottom of the border as shown.

What I claim is—

1. The design for wall paper herein shown and described.
2. In the design for wall paper, the border herein shown and described.

Witness my hand this 28th day of July, 1894.

CHARLES BOOZE.
